UNITED STATES PATENT OFFICE.

JOHN HARPER, OF PORTLAND, OREGON.

CONTROL FOR ELECTRIC FLATIRONS.

Application filed April 29, 1925. Serial No. 26,643.

This invention relates generally to electric flat irons, and particularly to means for controlling the temperature of the iron.

The first object of this invention is to provide an exceedingly simple and efficient control for the temperature of an iron which will cut off the supply of electrical energy when the iron reaches the maximum temperature desired, and to restore the supply when the temperature falls below a given point.

The second object is to eliminate the dangers from fires caused by the users of electric irons leaving same with the current turned on thereby permitting same to be over-heated and igniting surrounding objects.

The third object is to provide a special form of circuit-making and breaking device wherein the making and breaking of the circuit is made with a relatively rapid movement when compared with the ordinary slow movement of a thermostat.

The fourth object is to so construct the device that it will readily respond to changes of temperature in the iron and that it will be of a nature which will permit its installation in almost any type of iron with only a relatively small change being made therein.

Figure 1 is a vertical section through the device taken along the line 1-1 in Figure 3. Figure 2 is a vertical section taken along the line 2-2 in Figure 3. Figure 3 is a transverse vertical section taken along the line 3-3 in Figure 1. Figure 4 is a fragmentary vertical section similar to the upper portion of Figure 1 showing the circuit broken. Figure 5 is a fragmentary vertical section similar to the upper portion of Figure 2 showing the position of the parts, also during the time when the circuit is open. Figure 6 is a rear elevation for a flat iron showing the device attached and Figure 7 is a side elevation thereof.

Similar numbers of reference refer to the same parts throughout the several views.

Referring in detail to the drawing, there is shown for the purpose of illustration an electrical flat iron 10 provided with the usual handle 11 and a receptacle 12, which receptacle in this case must be slightly enlarged. In the receptacle are the usual contact posts 13 common to most electric irons. In the top of the iron is provided an opening 14 through which heat passes to the

temperature control device. This device consists of an outer shell 15 of insulating material which is provided with a side cover 16. The top 17 is closed, except for an opening 18 for wires 19 and 20 of the usual ironing cord. The lower portion 21 of the shell 15 is preferably provided with an opening 22 which is directly over the opening 14 in the iron 10. A second pair of openings 23 and 24 register with the contact posts 13. In enlarged portions of the openings 23 are placed the insulating bushings 25 and 26, in which are housed the U-shaped contact clamps 27 and 27^A to which are attached the wires 28 and 29 by means of the screws 30.

Above the member 21 and journaling in cups 31, which are mounted in the bosses 32 on the inner sides of the members 15 and 16, are the pivots 33 and 34. The pivot 34 is mounted on the side of the U-shaped housing 35 whose ends 36 are attached by means of the screws 37 to a disk 38 which is provided with openings 39 and 40.

A mercurial thermometer consisting of the lower bulb 41, which is placed within the opening 39, an upper bulb 42 in the opening 40 and a connecting tube 43. A quantity of mercury 44 is placed in the lower bulb 41.

A pair of straps 45 are placed around the tube 43 and are held by means of the screws 46 to the disk 38. A central strap 47 is attached to the disk 38 by means of the screws 48 and this strap carries the pivot 33.

Between the end walls 36 is placed the cylindrical container 49, preferably made of glass, and mounted concentrically with the pivots 33 and 34 between the curved blocks 50 against the members 36. A quantity of mercury 51 is placed in the container 49 and the space unoccupied by the mercury 51 is filled with inert gas.

In the upper side of the member 49 are introduced the two electrodes 52 and 53 which are adapted to dip slightly into the mercury 51 when the bottoms of the two electrodes are level. Flexible lead wires 54 and 55 connect the wires 28 and 19 with the electrodes 52 and 53.

A portion of the disk 38 is turned outwardly to form a lug 56 through which is passed a radial screw 57 whose head passes through a slot 58 in the top 17. Screws 59 are employed to hold the cover 16 in place on the outer shell 15.

The operation of the device is as follows:

When starting to iron, the parts take the position shown in Figures 1, 2 and 3 and current flows between the electrodes 52 and 53 to the heating element in the iron. When the temperature of the iron rises sufficiently and heat passes upwardly through the opening 22 and reaches the thermometer bulb 41, the mercury therein is forced to rise in the tube 43 and enters the bulb 42, thereby ⁵ stabilizing the rotatable parts which are mounted on the pivots 33 and 34. The screw 57 tends to unbalance these parts and causes same to take the positions shown in Figures 4 and 5 wherein it will be seen that the electrode 52 will be raised out of the mercury 51, thereby interrupting the flow of current to the iron. This condition will remain until the temperature of the iron drops sufficiently to allow the mercury to descend into the bulb 41, thereby increasing the stability ¹⁰ of the rotatable parts causing both of the electrodes 52 and 53 to touch the mercury 51 and restore the flow of current to the iron.

It will be noted that the thermometer bulb 41, with the tube 43 and the bulb 42, are made somewhat adjustable within the openings 39 and 40 in order to permit the best position for these parts. It is evident that the screw 57 can be adjusted from the exterior of the top 17 and that this adjustment will affect the temperature at which the circuit is closed or opened by the device.

It must be understood that it is not my intention to confine myself to this precise form ²⁵ or construction of parts, as many changes can be made in the details of this device without departing from the spirit of my invention.

I am aware that many forms of controls ³⁰ for electric flat irons have been constructed in the past; I therefore do not intend to cover same broadly but I do intend to cover all such forms and modifications thereof as fall fairly within the appended claims.

⁴⁵ I claim:

1. A temperature controlled switch having a casing; a rotatable disk mounted in said casing; a mercury reservoir bulb mounted on said disk below its center of rotation; an ⁵⁰ overflow bulb above said reservoir bulb; a tube connecting said reservoir and overflow bulb; a mercury containing contact chamber

on said disks; a pair of spaced electrodes normally touching the mercury in said container; and means for unbalancing said disk in a manner to raise one of said electrodes out of said mercury.

2. An electric switch having an outer casting; a disk rotatably mounted therein; a cylindrical container mounted on said disk ⁵⁵ having a quantity of mercury confined therein and having a pair of electrodes extending downwardly to said mercury; a mercury thermometer also mounted on said disk, said thermometer having an overflow bulb at its upper end above the axis of said disk, said casing having an opening therein adapted to communicate with a heated area, said disk having an adjustable weight mounted thereon adapted to unbalance same when the mercury rises into said overflow bulb.

3. A thermometer-controlled switching mechanism consisting of a mercury container having pivotal supports and having its bottom concentric with said pivots; mercury in ⁶⁰ said container; a pair of spaced electrodes mounted on said container and normally touching said mercury; a thermometer rotatable with said container and having its mercury containing bulb slightly below the axis of said container, said thermometer having an overflow bulb above said axis; and adjustable means for rotating said parts after they have been unbalanced by the mounting of the mercury into the overflow ⁶⁵ bulb.

4. A thermometer controlled switch consisting of a casing having an opening therein adapted to communicate with a heated area; a mercury container pivotally mounted within said casing having the lower side of its mercury-engaging portion concentric with said pivots; a pair of electrodes mounted on said container normally touching said mercury; a thermometer rotatably mounted ⁷⁰ with said container over said heat-conveying opening and having an overflow bulb on its upper end, said thermometer serving to unbalance said container when the mercury in said thermometer rises; and means for rotating said container consisting of a radial screw also adapted to act as a stop for the rotary movement of said container.

JOHN HARPER.
